UNITED STATES PATENT OFFICE.

WILLIAM H. BROWN, OF INDIANAPOLIS, INDIANA.

ILLUMINATED ANTISLIPPING WALK-WAY.

SPECIFICATION forming part of Letters Patent No. 629,950, dated August 1, 1899.

Application filed November 10, 1898. Serial No. 696,081. (No model.)

To all whom it may concern:

Be it known that I, WILLIAM H. BROWN, a citizen of the United States, residing at Indianapolis, in the county of Marion and State 5 of Indiana, have invented certain new and useful Improvements in Illuminated Antislipping Walk-Ways, of which the following is a specification.

The object of my said invention is to provide in such structures as sidewalks, area-ways, &c., used in situations where it is necessary not only to provide a walk-way, but to illuminate the space beneath, a construction which will be safe for passers-by to walk upon 15 without danger of slipping. As is well known, sidewalk-lights as usually constructed are quite dangerous in this particular, especially in wet or snowy weather, at which times the glass surface, as well as the surface of most 20 materials of which settings for the lights are made, is very slippery. Lead when properly arranged is peculiarly adhesive to the soles of boots and shoes, and my present invention consists in a peculiar construction and arrangement 25 whereby lead is utilized both as the setting for the glass lights or similar parts and as the contact-surfaces upon which the boots and shoes of passers-by will rest, as will be hereinafter more particularly described and 30 claimed. It will be understood that in all cases where in this specification and the appended claims I make use of the term "lead" I mean to be understood as including any 35 equivalent soft metal which may be used for the purpose.

Referring to the accompanying drawings, which are made a part hereof and on which similar reference characters indicate similar parts, Figure 1 is a perspective view illustrating the use of my said invention and also another invention in a sidewalk; Fig. 2, a top or plan view of one section of my improved sidewalk material as I have constructed the same ready to be put in place; Fig. 3, a top 45 or plan view of one corner of such a section, showing the full size which I have made and design to make the same; Fig. 4, a transverse sectional view on the dotted line 4-4 in Fig. 3, showing the construction more clearly; Fig. 5, a plan view similar to a portion of Fig. 3, the central portion being broken away and showing a horizontal section as the same ap-

pears at the intersection of the squares at points indicated by the dotted line 5-5 in Fig. 4; Fig. 6, a detail sectional view on the dotted line 6-6 in Fig. 3; Fig. 7, a view similar to Fig. 4, illustrating an alternative construction; Fig. 8, a view similar to Fig. 5 of the construction shown in Fig. 7, and Fig. 9 a detail sectional view similar to Fig. 6 of the construction shown in Figs. 7 and 8 on the dotted line 9-9 in Fig. 8.

In said drawings the portions marked A represent the framework, B the glass lights, and C the lead portions.

The frame A is preferably of cast-iron and is in form a sash, within the apertures of which the glass or parts B are to be secured. The preferred form of this frame or sash is best shown in Fig. 4, in which the ribs or those 70 portions of the ribs which extend up between the edges of the glass are of a dovetail formation for the purpose of securely anchoring the lead portions C. This form, however, being somewhat difficult to cast may be changed 75 and the ribs given the form shown in Fig. 7, in which case horizontal holes are made through said ribs at their intersections, into which the molten lead usually used will run and become anchored by the resulting cross-bars c, as is best shown in Figs. 8 and 9.

The spaces in the sash are of course of sufficient size to not only receive the lights of glass, but also the setting, and in order that said lights shall be held to position centrally 85 within the apertures which contain them while the setting is being inserted into place I provide low lugs a in the corners of the spaces, against which the lower portions of the corners of the lights or parts B shall immediately rest when put in place. These lugs hold said parts B in position until the lead forming the setting has been put in, and thus an even distribution of the lead around all the edges of the same is insured.

The lights or parts B are shown as rectangular, but they may obviously be of any other suitable form. They are beveled somewhat upon their edges, in order that the lead setting may be enabled to hold them more securely in place. I have shown said lights or parts as also recessed somewhat upon the under sides; but they are or may be in themselves of an ordinary and well-known form.

The portion C is formed of lead (or, as above stated, of other equivalent soft metal) and is inserted in around the lights or parts B, holding the same securely in place, and is also formed to project somewhat above the surface thereof and form the "tread" upon which the soles of the boots or shoes of passers-by will ordinarily come in immediate contact. The ribs or parting-strips *r* of the frame are made low enough so that the portions immediately over them shall be of considerable thickness, thus giving a large amount of material and enabling these parts to endure long wear. When the ribs are formed as shown in Fig. 4, such formation is in itself entirely sufficient to lock or anchor the parts firmly together. When the formation is as shown in Fig. 7, then the holes through the ribs at the corners or at other suitable points become necessary, in order that the lead setting may enter said holes, and thus be firmly anchored in place. The method of putting the lead portions C in position which I have adopted and prefer is to provide a plate containing grooves corresponding to the desired projection of the lead above the general surface of the structure, secure said plate over the frame or sash after the parts B are placed in position, and then pour the molten lead into the resulting openings or interstices, which will thus become filled thereby, as shown, and after the lead has become cooled the removal of the mold-plate leaves the structure complete and ready for use.

Such a structure has been proved by actual test to be highly efficient for the purpose. The projecting lead portions will wear a considerable time, and by the time they become

worn down the glass surfaces of the intervening lights will become abraded and rough, so as to be in themselves, in large measure, non-slipping, while of course the lead intervening strips will always maintain their non-slipping characteristics.

Having thus fully described my said invention, what I claim as new, and desire to secure by Letters Patent, is—

1. The combination, in an illuminated anti-slipping walk-way, of the frame or sash divided by low ribs into suitable spaces to receive the lights, said lights mounted therein, and the lead portions surrounding said ribs and filling the spaces between the edges of said lights and to a point above the surface of said lights, whereby said lead portions form the tread of said walk-ways, substantially as set forth.

2. The combination, of the frame or sash, A, having apertures adapted to contain lights with ribs, *r*, dividing the several spaces and small projections, *a*, in the corners of the apertures whereby the lights are held centrally therein before the setting is placed around them, said lights, B, and a lead setting, C, placed over said ribs and between the lights and serving also as antislipping strips, all substantially as and for the purposes set forth.

In witness whereof I have hereunto set my hand and seal, at Indianapolis, Indiana, this 8th day of November, A. D. 1898.

WILLIAM H. BROWN. [L. S.]
